COLLAPSIBLE CHAIR

George C. Herschell, Portland, Oreg.

Application December 10, 1956, Serial No. 44,142

Term of patent 14 years

(Cl. D15—1)

I claim:

The ornamental design for a collapsible chair, as shown.
